UNITED STATES PATENT OFFICE.

ANDREW C. NICOLS, OF YOUNGSTOWN, OHIO.

SAFETY DEVICE FOR POWER PRESSES.

Application filed November 3, 1923. Serial No. 672,662.

To all whom it may concern:

Be it known that I, ANDREW C. NICOLS, residing at Youngstown, in the county of Mahoning and State of Ohio, a citizen of the 5 United States, have invented or discovered certain new and useful Improvements in Safety Devices for Power Presses, of which improvements the following is a specification.

10 My invention relates to safety device for power presses. I have developed it as an accessory to a press for stamping, embossing and smooth plating leather and giving to the leather a proper condition of surface preparing it for the manufacture of all classes of finished leather products. In that association I shall show and describe it.

In the accompanying drawings, Fig. I is a view in side elevation showing diagrammatically the parts of a leather press and showing in detail the structure of the safety device applied thereto. It is essentially a view in elevation. A certain rail however is in part broken away and certain details are 25 there shown in section. The plane of section of this detail is indicated by the dotted line I—I, Fig. II. Fig. II is a view of the same assembly in side elevation. Fig. III is a view similar to Fig. II, from which however certain operating parts are omitted, in order to show more clearly certain characteristics of some of the remaining parts.

The press consists essentially of a stationary member 2 whose nether horizontally extending face is the working face, and a movable member 1 which in the operation of the press reciprocates vertically beneath the stationary member 2, and whose upper face cooperates with the nether face of the stationary member 2 in the operation of pressing. The bite between these press members is indicated at *a*. At 3 is diagrammatically indicated base block or bed of the press. It is of course stationary. Block 2 is spaced at a 45 sufficient interval above it, and block 1 is arranged between and reciprocates in the interval.

The movable member 1 carries a table 4. This table normally extends from the block 50 on one side, and normally in the horizontal plane which is substantially coincident with the horizontal face of the block 1.

This table 4 constitutes a rest for the work and, in the operation of the machine, 55 an attendant places the leather to be pressed

upon the table 4, and while it is resting upon the table 4 and while those members are open and in preparation for the pressing action, he advances it upon the upper face of the block 1 and into the bite *a* between press members 1 and 2. As is particularly shown in Figure III this table 4 is advantageously hinged to the block 1 so that it may be swung out of the way when there is need, as for instance when the machine is undergoing 60 repair, or when the dies for press members 1 and 2 are being replaced.

The table 4 carries a guard rail 7 reciprocable approximately in a plane coincident with the plane of the extent of the table 70 itself. To this end the guard rail 7 is conveniently borne upon rods 6, and these rods are extensible and retractile in guides or ways 5, conveniently formed upon the under side of table 4.

Means are provided to cause the guard rail 7 to be extended and retracted in alternation as the press members 1 and 2 close and open again.

To this end a lever or beam 8 is pivoted to 80 swing on a suitable post 9 borne by the movable member 1 of the press. At one end this lever 8 is by bars 10 and 11 so linked to the movable block 1 and to the base block 3 that vertical reciprocation of the block 1 will effect swinging of the lever 8. It should be remarked that the lever 8 is pivoted on a horizontal axis, and swings in a vertical plane. The lever 8 is at its opposite end linked to the rod 6, and the arrangement is 85 such that as the block 1 moves up and down, and as the lever 8 swings, the rod 6 will be shifted in the slideway 5 and the guard rail 7 will be alternately extended and retracted.

Figure II shows in full lines the member 90 1 in inactive or open position, and the guard 95 rail 7 retracted, and it indicates in dotted lines the member 1 in active and raised position, and the guard rail 7 extended. The positions of the actuating means are also in alternate positions clearly indicated and may readily be followed.

It remains to be said that the link 12 by which the lever 8 is connected with the rod 6 is connected by a pivot-pin 13 which manifestly may be made removable, and further that the rod 6 is provided with an extended plate 14, in which there is a succession of holes for the pivot pin. By making pivotal connection through one or another of these 100 110

holes the position of the guard rail 7 may be adjusted, and the effective range of its extension correspondingly adjusted.

The feature of a removable pivot pin is 5 advantageous, in that it allows for the swinging of the table out of the way, as I have suggested in Fig. III, when it is desired to have access to the press parts for such purposes as those indicated.

10 I have in the foregoing specification spoken of the rod 6, the lever 8 and the interconnecting parts in the singular. As is clearly indicated in Figure I these parts will ordinarily be duplicated on either side 15 of the machine, in order to insure smoothness of operation.

While I do not mean to limit myself to particular proportions it ordinarily will be true in the use of this machine that as the 20 attendant stands by the machine, the plane in which the pressing is effected is with respect to him approximately chest-high.

The dimensions of the table 4 and the 25 range of extension of the guard rail 7 are such that in case he should be negligent, the closing of the press members effecting extension of the guard rail will cause the guard rail to strike him on the chest, and the range will be such that the distance at which the 30 extended guard rail is remote from the meeting faces of the press will be approximately as great as the length of the attendant's arm. With the use of the invention so adjusted then it becomes practically impossible 35 for the workman through carelessness to have his hand caught between the closing members of the press, and that of course is the end desired.

It will be observed of this safety device 40 that it is simple in construction and therefore easily maintained in order and in good repair, that in operation there is no lost motion, there are no heavy strains, but the device functions with a minimum expenditure 45 of power, and an expenditure which is relatively insignificant. There is no upward thrust of heavy parts such as might throw undue heavy strain upon the essential elements of the press. The presence of the 50 table is itself a feature of safety, in that it makes it impossible for the operator, even

if the guard rail should under peculiar circumstances be ineffective, carelessly to reach the faces of the meeting dies with the consequences of having his hand caught. The 55 table of course has value in the operation of the machine, to afford a rest for the work and for the attendant's forearms. All of the equipment which goes to make up this safety device is arranged below the plane 60 in which the pressing operation is accomplished. It leaves the machine free and unencumbered to view at this point, and leaves the machine the more accessible for repairs, for the changing of dies, etc. The folding 65 of the table out of the way has been mentioned, and also the capacity of the safety device for adjustment, these being features which adapt it particularly to its intended use. 70

I claim as my invention:

1. In a power press including two members reciprocable one relatively to the other in vertical direction to and from a plane of meeting, a table hinged to one of said members and adapted to be swung from an active position of horizontal extension to an inactive and remote position, a guard rail borne by said table and extensible and retractable in the general plane of table extent, and means for effecting extension and retraction of said guard rail as the said press members reciprocate, said means engaging the guard rail by a separable pivot engagement. 85

2. In a power press the combination of the relatively movable press members 1 and 2, the hinged table 4, a swinging lever 8 borne by one of said members, the guard rail 7 extensibly borne by said table, means for swinging said lever as the press members close and open again, and means for imparting motion from the swinging lever to the guard rail, effecting extension and retraction thereof. 90

In testimony whereof I have hereunto set my hand.

ANDREW C. NICOLS.
